United States Patent Office

Des. 206,829
Patented Jan. 31, 1967

206,829

BOTTLE

Eugene Darcy, Hollywood, Calif., assignor to Consolidated Foods Corporation, a corporation of Maryland

Filed Sept. 27, 1965, Ser. No. 87,175

Term of patent 14 years

(Cl. D58—6)

FIG. 1.

FIG. 2.

FIG. 3.

FIG. 4.

FIG. 5.

FIG. 6

FIG. 1 is a top plan view of a bottle showing my new design;

FIG. 2 is a side elevational view thereof;

FIG. 3 is a bottom plan view thereof;

FIG. 4 is a longitudinal partial sectional view thereof;

FIG. 5 is a transverse sectional view taken on the line

5—5 of FIG. 4; and

FIG. 6 is a transverse sectional view taken on the line

6—6 of FIG. 2.

I claim:

The ornamental design for a bottle, as shown.
